UNITED STATES PATENT OFFICE.

GEORGE E. BOWERS, OF FITCHBURG, MASSACHUSETTS.

MAGNET FOR SEPARATING IRON CHIPS.

SPECIFICATION forming part of Letters Patent No. 240,956, dated May 3, 1881.

Application filed August 2, 1880. (Model.)

To all whom it may concern:

Be it known that I, GEORGE E. BOWERS, of Fitchburg, Worcester county, State of Massachusetts, have invented a new and useful Improvement in Magnets for Separating Iron Chips, of which the following is a specification.

Permanent magnets have heretofore been used for separating particles and chips of iron from lathe-turnings; but such magnets are of limited power and become less powerful by use. Further than this, a brush is required for separating the iron from the magnet.

The object of my invention is to obtain a powerful magnet for the purposes named, and to save the time and labor required generally for removing the chips from the magnet.

My invention consists in a magnet having a straight core and helices wound in opposite directions inclosed in a tube or hollow cylinder that is attached to one pole of the magnet, and also provided with a switch, whereby the direction of the current around a portion of the magnet can be reversed, so as to demagnetize the core and cylinder and thereby release the chips.

In the accompanying drawings, forming a part of this specification, Figure 1 is a longitudinal section of my improved magnet. Fig. 2 is an end view, showing the reversing-switch; and Fig. 3 is a cross-section on line *x* *x*, Fig. 1.

Similar letters of reference indicate corresponding parts.

A is the core of the magnet fitted with a wooden spool, *a*, around which is the main helix *b* and also the smaller helix *c*, wound in reverse direction. One end of each helix is connected with core *A*, while their other ends extend beneath opposite ends of key *d*, that is hung on an insulated support, *e*, at one end of

the magnet. The key *d* carries a binding-post, *f*, and by a spring, *g*, is held normally in contact with the end of main helix *b*. The other binding-post, *h*, is in connection with the core.

B is a metal tube surrounding the two helices 45 and attached to the **S**-pole of the core.

This form of magnet gives extended surface for adherence of the particles of iron and sufficient power, as required.

By pressing down key *d* the circuit is broken 50 in the main helix *b*, and established in the small helix, thereby demagnetizing the core and tube so that the chips can drop from the magnet by gravity. The small helix is sufficiently large to neutralize the residual magnetism without instantly inducing magnetism of sufficient strength to prevent the chips from falling.

By a magnet of this construction iron chips can be readily separated from brass and other 60 particles and the work done rapidly.

Having thus described my invention, I claim as new and desire to secure by Letters Patent—

1. The insulated key *d* and binding-post *f*, 65 combined with a magnet having helices *b* *c* wound in opposite directions, and inclosing-tube *B*, substantially as and for the purposes set forth.

2. An electro-magnet for separating iron 70 chips from other materials, consisting of the central core, *A*, the helices *b* *c*, wound in opposite directions, the inclosing-tube *B*, the key *d*, and the binding-posts *f* *h*, substantially as herein shown and described.

GEORGE EGBERT BOWERS.
